UNITED STATES PATENT OFFICE.

HENRI VICTOR JULES JOUFFRET, OF NEUILLY, SEINE, FRANCE.

INTERNAL-COMBUSTION ENGINE.

1,363,123.

Specification of Letters Patent. Patented Dec. 21, 1920.

Application filed June 10, 1918. Serial No. 239,250.

To all whom it may concern:

Be it known that I, HENRI VICTOR JULES JOUFFRET, engineer, a citizen of the French Republic, residing at Neuilly-sur-Seine, Department of Seine, France, have invented 5 certain new and useful Improvements in Internal-Combustion Engines, of which the following is a specification.

This invention relates to internal combustion engines, and particularly that type 10 wherein the compression must be augmented under certain conditions and commonly known as surcompression engines. In internal combustion engines adapted for aero- 15 planes it is well known that provision must be made for normal operation of such engines at certain elevations where the atmospheric air pressure is materially reduced. These engines, when at the earth's surface, 20 suck up too great amount of air if the admission means or inlet for the air is unrestrictedly open and as a consequence there is too strong air compression for practical operation. The present invention concerns 25 a device or means for automatically controlling the air admission so that the air compression remains normal at the earth's surface as well as at certain high elevations and whereby too great compression cannot 30 take place.

The invention has for its principal object 35 the construction of apparatus of the class in question, so that it is more simple and at the same time operates in a more satisfactory manner than has previously been the case.

According to the general principle of my 40 invention, in constructing apparatus of the class in question, I provide a balanced mechanism, subjected in one direction to the action of a constant force and in the other direction to the combined actions of a suction approximately constant and of the variable pressure existing in the chamber or 45 conduit where the pressure is to be regulated by the apparatus.

In addition to the foregoing principal 50 constructional feature or arrangement, the invention also includes other features which will be more fully described hereafter.

It includes certain embodiments of the 55 said improvements or features, apparatus having the said improvements applied thereto, as new articles of manufacture, special parts for their construction and plant and engines provided with the improvement.

And in order that the said invention may be clearly understood, I will now proceed to describe the same with reference to the accompanying drawing, which however is given merely by way of example.

Figures 1 and 2 of the said drawing are diagrammatic sections of two sets of controlling apparatus constructed respectively according to a first and to a second method of carrying out my invention.

Fig. 3 is an elevation of an apparatus constructed according to a third method of carrying out my invention.

The apparatus, about to be described with reference to the drawing, embodies methods of carrying out the invention as applied to a motor for aviation purposes working with automatically augmented compression, and provided with means for regulating the intake of air for maintaining the rate or value of the volumetric compression of the said motor constant for all atmospheric pressures below a predetermined value. The embodiments are however, as previously stated, only typical and I may proceed in some other equivalent or analogous manner.

Referring to the drawing, *a* is a chamber divided into two compartments *a*¹ and *a*², by a device *b* which may consist of a dia- 85 phragm, but preferably, as shown in the drawing, of a piston adapted to move in the chamber *a*.

I connect one of the compartments *a*¹ to an apparatus, such as a pump *c*, adapted to 90 produce in the said compartment, a suction, which is substantially constant. I connect the other compartment *a*², by a conduit *a*²⁰ with the aspirator tube *d* of the motor.

I mount, in the admission orifice or passage of the said tube *d*, an obturator or obturating device *e* of a balanced type, in such a way that the said device will have a tendency to open widely under the action 100 of a constant force, exerted either by its own weight or by a spring *e*⁰.

I may, as shown at Figs. 1 and 2, form the said device *e* as a balanced valve, in which case, as shown at Fig. 1, I connect the 105 said valve *e* by a stem *b*¹ to the piston *b*, in such a way that the constant force tending to open the valve *e* also tends to displace the piston in a direction opposite to that in which it would be displaced under the 110 action of the suction produced by the pump *c*; or else, as shown at Fig. 2, I may pro-

vide the chamber a inside the valve e , making, in the piston b , a conduit b^{10} adapted to connect the compartment a^1 of the said chamber with the pump c .

5. On the other hand, as shown at Fig. 3, I may produce an effective result by forming the device e as a simple oscillating shutter of a suitable balancing thickness.

With this construction, I connect the 10 arm e^1 which is adapted to operate the shutter by a rod b^1 to the piston b , and arrange that the constant force, which in this instance is a spring e^0 , tends to open the shutter and to displace the piston b in a direction opposite to that in which it tends to be displaced under the action of the suction produced by the pump c .

In the foregoing manner, I obtain a pressure controlling apparatus, in the case of 20 which all variations of pressure in the interior of the tube d produce a displacement with respect to one another of the chamber a and the piston b , the result of such displacement being to modify the sectional area 25 of the admission passage for air into the tube, and consequently the pressure in the said tube. This displacement only ceases to operate when there is equilibrium on the one hand between the action of the constant 30 force—weight or spring—tending to open the device e and, on the other hand, the combined action of the suction which is substantially constant and produced in the compartment a^1 , by the pump c and of the pressure in the tube d which operates in the compartment a^2 , through the conduit a^{20} that is to say when the pressure in the tube d has been lowered to a predetermined value.

It is to be observed that the suction exerted by the pump c may be of any value 40 whatever, provided it remains constant, and that it is not necessary for the piston b to work tightly in the chamber a .

It will of course be understood that I 45 provide in addition suitable means for maintaining constant, whatever may be the atmospheric pressure, the supply of fuel, and for this purpose I may for instance provide the float chamber of the carburetor with 50 a closed or tight cover and connect the interior of the said float chamber to the tube d .

In the case where I utilize controlling 55 means of the kind shown at Fig. 3, in particular, I may provide, in series, in the tube, several pressure controlling apparatus of the kind described, to avoid the fear of accident, in case one of the apparatus ceases to operate, the regulation being in that case effected by the device in action nearest to 60 the opening for admission of the tube.

It is to be understood that the invention is not limited in the particular methods of

carrying out the same which have been just described, but that all modifications are included coming within a fair interpretation 65 of the claims.

Claims:

1. Regulating or controlling means of the class specified and applicable to internal combustion engines, comprising an aspirator tube, a chamber provided with means for dividing the same into two compartments, one of the compartments being in communication with the said tube, an obturating device co-operating with said means for controlling an air inlet to said tube, and means for producing a suction in the remaining compartment, whereby the value of the volumetric compression may be maintained constant for all pressures of the atmosphere below a predetermined value. 70

2. In a regulating or controlling means of the class specified, a chamber having means for dividing the same into two compartments, a suction pump connected to one of 85 the compartments, and an aspirator tube in communication with the remaining compartment for the purposes specified.

3. A regulating means applicable to internal combustion engines for maintaining 90 the value of the volumetric pressure constant for all atmospheric pressures below a predetermined value, comprising a chamber provided with a balanced part for dividing the same, a tubular means in communication with a part of said chamber and in which the pressure is to be regulated, and means for exerting a constant suction in one direction on said balanced part in opposition to the normal tendency of said part to 95 open an air inlet to said tubular means. 100

4. In regulating or controlling means of the class specified, a chamber having an obturating device of a balanced type co-operating therewith, suction means connected to 105 one part of the chamber, and an aspirator tube in communication with another part of said chamber.

5. A regulating or controlling means of the class specified consisting of an aspirator 110 tube, a balanced obturator mounted in the said tube and having a chamber divided into two compartments, one of the compartments being in communication with the tube, and suction means connected to the remaining compartment of the chamber. 115

In testimony whereof I have hereunto set my hand in presence of two subscribing witnesses.

HENRI VICTOR JULES JOUFFRET.
